(57) **CLAIM**

The ornamental design for an electric nail file as shown and described.

DESCRIPTION

FIG. 1 is a first perspective view of an electric nail file showing my new design;

FIG. 2 is a second perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a perspective view thereof together with a charging stand before assembly; and,

FIG. 10 is a perspective view thereof assembled with the charging stand.

The broken lines in the drawings illustrate portions of the electric nail file which form no part of the claimed design. The broken lines of the charging stand applied to the electric nail file in FIGS. 9-10 are used to indicate environmental structures and form no part of the claimed design.
